CLAIM

The ornamental design for a portable solar power generator, as shown and described.

DESCRIPTION

FIG. 1 is a plan view of the portable solar power generator showing my new design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a bottom plan view thereof; and,

FIG. 7 is a perspective view thereof. The broken lines shown in FIG. 7 indicate an optional AAA adapter and do not form a part of the basic design.

UNITED STATES PATENT AND TRADEMARK OFFICE
CERTIFICATE OF CORRECTION

PATENT NO. : Des. 467,225 S
DATED : December 17, 2002
INVENTOR(S) : Makoto Sudo

Page 1 of 1

It is certified that error appears in the above-identified patent and that said Letters Patent is hereby corrected as shown below:

Title page.

Item [76], the inventor's address should read as follows:

-- Flat A, 32nd Floor, Tregunter Tower 1,14
Tregunter Path, Hong Kong --

Signed and Sealed this

Third Day of June, 2003

JAMES E. ROGAN
Director of the United States Patent and Trademark Office
